UNITED STATES PATENT OFFICE.

FRANK S. THORNE, OF PORTLAND, OREGON.

FIREPLACE AND BACK.

1,250,712.

Specification of Letters Patent. Patented Dec. 18, 1917.

Application filed May 27, 1916. Serial No. 100,386.

To all whom it may concern:

Be it known that I, FRANK S. THORNE, a citizen of the United States, residing at Portland, in the county of Multnomah and 5 State of Oregon, have invented certain new and useful Improvements in Fireplaces and Backs; and I do hereby declare the following to be a full, clear, and exact description of the invention, such as will enable others 10 skilled in the art to which it appertains to make and use the same.

This invention relates to certain new and useful improvements in fireplaces, and refers more especially to that class wherein a novel 15 form of fire-back is used for deflecting the heat.

An object of the present invention is the production of an open fireplace including an inclined fire-back formed with grooves 20 for radiating a maximum amount of heat outwardly into the room.

Another object of this invention is to produce an open fireplace having embedded 25 in the rear wall thereof a fire-back formed with V grooves extending from substantially the lower central portion and edge thereof upwardly in diverging directions to a position near the top of said fire-back, whereby the flames are spread, and a maximum heat radiating and deflecting surface 30 is produced.

A further object of this invention is the production of an open fireplace comprising a novel form of grooved fire-back, a readily 35 removable grate positioned below said fire-back, and damper controlled draft passages below said grate arranged to admit air on three sides of the fireplace beneath the grate.

With these and other objects in view the 40 invention further consists in the novel arrangement and combination of the several parts hereinafter described and claimed.

In the drawing which shows by way of illustration an embodiment of the invention,

5 Figure 1 is a front elevation of the fireplace with the fire-back in position.

Fig. 2 is a vertical sectional view there- 45 through.

Fig. 3 is a horizontal sectional view on line 3—3 of Fig. 2.

Fig. 4 is a detached face view of the fire-back removed.

Fig. 5 is a similar view of a modified form of fire-back, and

5 Fig. 6 is a sectional view on the line 6—6 of Fig. 4.

The present invention has been designed for producing greater radiation of heat from a fireplace of this type and at the same time proportionately reducing the quantity of 60 fuel consumed. The novel form of fire-back formed with V grooves diverging upwardly in arcuate paths affords an increased radiating surface for spreading the flames and deflecting the heat outwardly as 65 will be hereinafter described.

Referring to the drawings, in which similar reference characters designate corresponding parts, the fire-place 1 comprises a back wall 2, which is inclined forwardly 70 as at 3 and receives the fire-back; and opposite angularly disposed side walls 4 and 5. The walls are built of any suitable material such as fire-brick, ornamental stone or other available substances, and as shown 75 unite at the top of the fireplace to form the usual flue 6.

The grate 7 is positioned in the fireplace within a frame 8 suitably mounted upon the projecting portion of the back wall 2, 80 see Fig. 2. This grate is removable and as shown is formed with hook members 9 adapted to engage openings 10 provided in the frame 8, whereby the grate can be either swung, or entirely removed, as may be desired. A lug 11 extends from the frame 8 and supports the front edge of the grate. The usual ash receiver (not shown) is preferably located beneath the grate into which the ashes from the fire are deposited. 90

A fuel retaining guard 12 is provided on the outer edge of the frame 8, and extends across the front of the fireplace. Thus it will be seen that when coal is used as a fuel the bed of the fire can be easily retained within the fireplace at a convenient level beneath the fire back. 95

The dampers for controlling the draft to the fire are located on each side and in front of the fireplace beneath the grate. 100

The dampers 13 and 14 are located on opposite sides of the fireplace, and control the passage of air through draft flues 15 and 16. The door 17 extending across the front of the fireplace and positioned within the 105 vertical guides 18 also acts as a damper for controlling the front draft to the fire. A suitable knob 19 is secured to the door for operating same.

By this construction of draft flues on each 110 side of the fireplace it will be seen that the air which is drawn in to aid the fire in burn-

ing is not the warm air which has been emitted into the room.

On the other hand, it is air drawn from without, of a pure nature, readily heated, 5 and quickly radiated into the room in a fresh and warm condition.

These opposite draft passages 15 and 16 operate equally well when an ordinary log or wood fire is kindled in the fireplace, and 10 any tendency of said fire to discharge smoke into the room can be easily remedied by an adjustment of the dampers.

Thus it will be seen that an efficient and easily operated fireplace has been produced, 15 in which the fuel can be readily handled, its consumption economically regulated, and a maximum amount of pure air admitted for purposes of heating the room under the very best of health conditions.

20 Coöperating with the fireplace hereinbefore described is a fire-back 20, embedded in the inclined portion 3 of the back wall 2. The fire-back is sufficiently inclined to deflect the greater portion of the heat from 25 the fire outwardly into the room, see Fig. 2.

V grooves 21 are formed on the face 22 of the fire-back exposed to the flames of the fire, and as shown extend upwardly in diverging directions from the lower central portion and edge of the said fire-back. 30 These grooves terminate short of the top edge of the fire-back into beveled portions 23 which merge into the face of the fire-back. In the form of grooves shown in 35 Figs. 1, 2, 3 and 4, the divergence of the said grooves is illustrated in the general form of an inverted Gothic arch, beginning on a common center line 24 and the lower edge of the fire-back, and curving upwardly 40 and outwardly. The angles of the grooves can be slightly varied to suit different design fireplaces, but I have found that a substantially 45° angle radiates and deflects the heat from the flame satisfactorily (see Fig. 45 6). In some instances these angles may be varied so as to deflect the heat clear of the side walls of the fireplace. In providing these angular grooves and terminating beveled portions it will be seen that the flame 50 is effectively conducted and spread to all parts of the fire-back, and a correspondingly increased volume of heat emitted from the fireplace.

In the form of fire-back shown in Fig. 5 55 of the drawing, the same general divergence of V grooves is illustrated, but instead of

curving the grooves, they are angularly inclined upwardly and outwardly as indicated at 25. These grooves terminate short of the upper edge of the fire-back in beveled 60 portions 26 which merge into the face of the fire-back as heretofore described.

While I have shown only two forms of V grooves it will be understood that various other designs can be substituted provided 65 the divergence of the angular grooves begins at the lower edge of the fire-back and extends upwardly and outwardly toward the top edge thereof so as to spread and deflect the flames and resulting heat to a maximum 70 degree.

From the foregoing it will be obvious that an improved fireplace and fire-back have been produced, the latter of which has been designed to conduct the passage of the 75 flames in diverging directions upwardly, thoroughly spread and deflect them, and finally emit an increased volume of heat from the fireplace.

Having thus described my invention, what 80 I claim and desire to secure by Letters Patent is:

1. A fireback comprising a flat plate having a series of V grooves formed on the front thereof, said grooves extending in an upwardly diverging direction from each other and from the central lower edge of the fireback to a point short of the upper edge of said fireback.

2. A fireback comprising a flat plate having two series of adjacent V grooves formed on the front thereof, said grooves extending in an upwardly diverging direction from each other and from the central lower edge of the fireback and flush with the outer surface thereof, to a point short of the upper edge of said fireback.

3. A fireback comprising a flat plate having a series of V shaped grooves arcuately formed on the front thereof, said grooves extending in an upwardly diverging direction from each other and from the central lower edge of the fireback to a point short of the upper edge thereof.

In testimony whereof I affix my signature, in presence of two subscribing witnesses.

FRANK S. THORNE.
